DESIGN FOR A SLIPPER

Jack Macht, New York, N. Y., assignor to Consolidated Slipper Corporation, Bombay, N. Y., a corporation of New York

Application January 16, 1939, Serial No. 82,372

Term of patent 3½ years

To all whom it may concern:

Be it known that I, Jack Macht, a citizen of the United States and resident of the city, county, and State of New York, have invented a new, original, and ornamental Design for a Slipper, of which the following is a specification, reference being had to the accompanying drawing, forming part thereof.

I claim:

The ornamental design for a slipper substantially as shown.

JACK MACHT.
